UNITED STATES PATENT OFFICE.

MORRIS SCHWARTZ, OF CHICAGO, ILLINOIS, ASSIGNOR OF ONE-HALF TO WINNIFRED B. PARISH, OF CHICAGO, ILLINOIS.

BUSHING STRUCTURE.

Application filed May 12, 1923. Serial No. 638,550.

To all whom it may concern:

Be it known that I, MORRIS SCHWARTZ, citizen of the United States, residing at Chicago, in the county of Cook and State of Illinois, have invented a certain new and useful Improvement in Bushing Structures, of which the following is a full, clear, concise, and exact description.

My invention relates to bushings and bodies to which they are applied and has for its object the provision of a construction whereby tags may be effectively assembled with such bushings and bodies.

The invention is of particular service in the construction of barrels in which the bores of the bushings constitute the bung holes of the barrels. In accordance with the invention the wall of a barrel having such bushing is formed with a ridge which is spaced apart from the opening receiving the bushing. The bushing itself is formed with a projection that is received in the space between the ridge and the opening that receives the bushing and the tag is clamped between the projection upon the bushing and the body receiving the bushing. This tag may be put to any selected use. I have employed it as an element of a seal to guard against the unauthorized opening of the barrel equipped with it. When the tag is thus employed the bung received in the bushing and the tag are formed with apertures to receive a sealing wire or string.

The invention will be more fully explained by reference to the accompanying drawing in which Fig. 1 is an end view, with parts broken away, showing a portion of a barrel head equipped with a structure of my invention; Fig. 2 is a sectional view on line 2—2 of Fig. 1 with parts shown in elevation; and Fig. 3 is a perspective view showing the bushing and its supporting body in separated relation and the tag placed in the position in which it is to be clamped.

Like parts are indicated by similar characters of reference throughout the different figures.

The barrel wall or other supporting body 1 is preferably formed of sheet material such as steel. It carries a tubular portion 2 which is preferably integrally formed therewith and projects to one side thereof. The body 1 is formed with a circumscribing bead or ridge 3 which bulges from the side

of the body that is opposite the free end of the tubular portion, this bead being spaced apart from the opening which receives the cylindrical bushing portion 4 and being desirably polygonal in contour to form a 60 pocket to receive the flange or projection 5 of the bushing whose exterior edge is similar in contour to the contour of the bead and is engageable with the inner side of the bead to prevent the bushing from turning upon its support when the bushing is guarded against axial movement with reference to said support as by means of a flange 6 curled to engage the inner end of the tubular portion 2. This characteristic forms the subject matter of my co-pending application 70 Serial No. 573,270, filed August 17, 1922.

The tag 7, preferably of strip metal, overlies the bead at two adjacent angularly related portions thereof and is clamped at its inner end between the flange 5 and body 1. The curled flange 6 serves to clamp the inner end of the tag between the flange 5 and the body 1. The ridge prevents the tag from being withdrawn laterally, and by placing the tag over a corner of the ridge it cannot be moved along the ridge.

As illustrated, there is a sealing gasket 8 clamped between the flange and the body portion 1 of the barrel, the space between the inner end of the tag and the opening which receives the bushing being sufficient to receive the gasket in the same plane with the inner end of the tag. When the structure is employed to furnish bung holes the interior of the bushing may be threaded to receive the threaded portion of the bung 9. When the tag is to form an element of a seal to guard against the unwarranted removal of the bung the tag is formed with an aperture 10 and some portion of the bung, say the ear 11 formed on its flange 12, is formed with an aperture 13. A sealing wire or string 14 is passed through the apertures 10 and 13 and its ends are sealed together by 100 a seal 15.

While I have herein shown and particularly described the preferred embodiment of my invention I do not wish to be limited to the precise details of construction shown as changes may readily be made without departing from the spirit of my invention, but having thus described my invention I claim as new and desire to secure 105 by Letters Patent the following:— 110

1. The combination with a body formed with an opening therethrough and having a ridge spaced apart from said opening; of a bushing in said opening and formed with a projection received in the space between said ridge and opening; and a tag having an inner end extending between said projection and body and clamped in place by said projection.
- 10 2. The combination with a body formed with an opening therethrough and having a ridge spaced apart from said opening; of an interiorly threaded bushing in said opening and formed with a projection received in the space between said ridge and opening; a tag having an inner end extending between said projection and body and clamped in place by said projection; and a bung received within and in threaded engagement with said bushing, the outer portions of said tag and bung being formed with apertures for the reception of a sealing wire or string.
- 15 3. The combination with a body formed with an opening therethrough and having two adjacent angularly related ridge portions spaced apart from said opening; of a bushing in said opening and formed with a projection received in the space between said ridge portions and opening; and a tag engaging both of said ridge portions and extending between said projection and body and clamped in place by said projection.
- 20 4. The combination with a body formed with an opening therethrough and having two adjacent angularly related ridge portions spaced apart from said opening; of an interiorly threaded bushing in said opening and formed with a projection received in the space between said ridge portions and opening; a tag engaging both of said ridge portions and extending between said projection and body and clamped in place by said projection; and a bung received within and in threaded engagement with said bushing, the outer portions of said tag and bung being formed with apertures for the reception of a sealing wire or string.
- 25 5. The combination with a body formed with an opening therethrough and having two adjacent angularly related ridge portions spaced apart from said opening; of an interiorly threaded bushing in said opening and formed with a projection received in the space between said ridge portions and opening; a tag engaging both of said ridge portions and extending between said projection and body and clamped in place by said projection; and a bung received within and in threaded engagement with said bushing, the outer portions of said tag and bung being formed with apertures for the reception of a sealing wire or string, the outer end of the projection upon the bushing conforming in contour to and closely approaching the inner contour of said ridge portions to hold the bushing from rotation.
- 30 6. The combination with a body of sheet material having a tubular portion integrally formed therewith and a bead spaced apart from the bore of said tubular portion and also integrally formed therewith and projecting from said body oppositely to said tubular portion; of a bushing in the bore of said tubular portion and formed with a projection received in the space between said bead and the bore of said tubular portion; and a tag having an inner end extending between said projection and body and clamped in place by said projection.
- 35 7. The combination with a body of sheet material having a tubular portion integrally formed therewith and a bead spaced apart from the bore of said tubular portion and also integrally formed therewith and projecting from said body oppositely to said tubular portion; of an interiorly threaded bushing in the bore of said tubular portion and formed with a projection received in the space between said bead and the bore of said tubular portion; a tag having an inner end extending between said projection and body and clamped in place by said projection; and a bung received within and in threaded engagement with said bushing, the outer portions of said tag and bung being formed with apertures for the reception of a sealing wire or string.
- 40 8. The combination with a body of sheet material having a tubular portion integrally formed therewith and a bead spaced apart from the bore of said tubular portion and also integrally formed therewith and projecting from said body oppositely to said tubular portion; said bead having two adjacent angularly related portions; of a bushing in the bore of said tubular portion and formed with a projection received in the space between said bead and the bore of said tubular portion; and a tag having an inner end extending between said projection and body and clamped in place by said projection, this tag engaging both of the angularly related portions of said bead.
- 45 9. The combination with a body of sheet material having a tubular portion integrally formed therewith and a bead spaced apart from the bore of said tubular portion and also integrally formed therewith and projecting from said body oppositely to said tubular portion, said bead having two adjacent angularly related portions; of an interiorly threaded bushing in the bore of said tubular portion and formed with a projection received in the space between said bead and the bore of said tubular portion; a tag having an inner end extending between said projection and body and clamped in place by said projection, this tag engaging both of the angularly related portions of said bead;
- 50 100
- 55 105
- 60 110
- 65 115
- 70 120
- 75 125
- 80 130

and a bung received within and in threaded engagement with said bushing, the outer portions of said tag and bung being formed with apertures for the reception of a sealing 5 wire or string.

10. The combination with a body of sheet material having a tubular portion integrally formed therewith and a bead spaced apart from the bore of said tubular portion and 10 also integrally formed therewith and projecting from said body oppositely to said tubular portion, said bead having two adjacent angularly related portions; of a bushing in the bore of said tubular portion and 15 formed with a projection received in the space between said bead and the bore of said tubular portion; and a tag having an inner end extending between said projection and body and clamped in place by said projection, this tag engaging both 20 of the angularly related portions of said bead, the projection upon the bushing conforming in contour to and closely approaching the inner contour of said angularly related bead portions to hold the bushing from 25 rotation; and a bung received within and in threaded engagement with said bushing, the outer portions of said tag and bung being formed with apertures for the reception of a sealing wire or string.

11. The combination with a body of sheet material having a tubular portion integrally formed therewith and a bead spaced apart from the bore of said tubular portion and 30 also integrally formed therewith and projecting from said body oppositely to said tubular portion, said bead having two adjacent angularly related portions; of an internally threaded bushing in the bore of said

tubular portion and formed with a projection received in the space between said bead and the bore of said tubular portion; a tag having an inner end extending between said projection and body and clamped in place by said projection, this tag engaging both 35 of the angularly related portions of said bead, the projection upon the bushing conforming in contour to and closely approaching the inner contour of said angularly related bead portions to hold the bushing from 40 rotation; and a bung received within and in threaded engagement with said bushing, the outer portions of said tag and bung being formed with apertures for the reception of a sealing wire or string.

12. The combination with a body formed with an opening therethrough and having two adjacent angularly related ridge portions spaced apart from said openings; of a bushing in said opening and formed with a 50 projection received in the space between said ridge portions and opening; and a tag overlying both of said ridge portions and extending between said projection and body and clamped in place by said projection, the 55 outer end of the projection upon the bushing conforming in contour to and closely approaching the inner contour of said ridge portions to hold the bushing from rotation.

In witness whereof, I hereunto subscribe 60 my name this 14th day of March, A. D. 1923.

MORRIS SCHWARTZ.
